R. J. LEWIS

TYPEWRITING MACHINE

Filed Dec. 29, 1925

Patented June 14, 1927.

1,631,970

UNITED STATES PATENT OFFICE.

RICHARD J. LEWIS, OF MOHAWK, NEW YORK, ASSIGNOR TO REMINGTON TYPEWRITER COMPANY, OF ILION, NEW YORK, A CORPORATION OF NEW YORK.

TYPEWRITING MACHINE.

Application filed December 29, 1925. Serial No. 78,146.

My invention relates to braking devices for typewriting machines, and its object is to provide a new and improved braking contrivance which is simple in construction, 5 easy to adjust and readily applicable to existing styles of typewriting machines.

To the above and other ends which will hereinafter appear, my invention consists in the features of construction, combinations of 10 devices and arrangements of parts herein-after described and particularly pointed out in the claims.

In carrying out my invention in the present instance I provide a braking device or 15 arm which is engaged by the feed rack on the carriage when it is operated to release the carriage, as for tabulating, said braking arm coacting through the rack with the carriage to exert a braking effect thereon during the tabulating run. The braking arm is 20 perforated to fit loosely and slidably on an upright stationary rod or guide around which, below the arm, is coiled a wire spring on which the arm rests, providing a yielding 25 cushion or support. Adjustable on the rod above the arm is a thumb nut whereby the amount of spring pressure on the arm may be varied, said nut also serving as an 30 abutment or pivot on which the arm may turn or swivel during the braking action. A guide cooperates with a slot in one end of the braking arm to prevent it from turning about the rod and thus becoming displaced relatively to the rack.

My invention will be described in detail 35 in connection with the accompanying drawings wherein

Fig. 1 is a fragmentary rear elevation, 40 partly in section, of a typewriting machine to which my invention is shown as applied, only so much of the machine being illustrated as is necessary to a full understanding of the invention.

Fig. 2 is a fragmentary plan view of the 45 braking device together with its support and certain cooperating parts.

Fig. 3 is a vertical sectional view of the 50 braking device and associate parts.

Fig. 4 is a view corresponding to Fig. 3 55 but omitting some of the parts shown therein and illustrating the braking device in operative relationship with the feed rack or bar.

Fig. 5 is a detached perspective view of 60 the braking arm.

I have shown the preferred form of my invention as applied to a No. 12 Remington typewriting machine and in association with a tabulating mechanism invented by George A. Seib, but it is, of course, to be understood 60 that the invention may be applied to other styles of typewriting machines and used in connection with other forms of tabulating mechanism as well as in other ways, or wherever it may be desired to apply a braking, 65 retarding or restraining action on the carriage or moving element.

In the drawing, the main frame, as shown, 70 comprises a base 1, posts 2 and a top plate 3. Fixed above the top plate are front and rear guide rails, the rear rail 4 being shown, 75 said rails cooperating through anti-friction rollers 5, with the front and rear bars of a traveling platen carriage, only the rear bar 6 whereof appears in the drawings. Mounted 80 on the carriage is a platen 7. Said carriage is constantly urged leftward along its track-ways by a motor or spring drum 8, which is mounted on the main frame and is connected by a band or strap 9 with the carriage. Pivoted at 10 to brackets 11 on the carriage bar 6 is a supporting frame 12 to 85 which is fixed a bar or feed rack 13, the lower edge of which is toothed to cooperate with a feed pinion 14, said pinion being mounted at the front end of a shaft 15 which takes bearings in a bracket or support 16, the latter being detachably secured to the upper part of a hanger or bracket member 17 which in turn is fixed to the top 90 plate. The means for detachably securing the upper bracket 16 to the under bracket or hanger 17 comprises at the right (viewed 95 from the rear, as in Fig. 1) the usual counter-sunk headed screw 18, while at the left there is employed a screw member or stud, indicated as a whole by the numeral 19, this stud being of a special design, employed for the purposes of my invention as 100 hereinafter explained. As best shown in Fig. 3, said stud 19 comprises a body portion 20, a lower threaded portion 21 and an upper threaded portion 22 of smaller diameter. Between the body portion and the 105 upper threaded end portion 22 there intervenes a hexagonal head portion 23 whereby the stud may be readily screwed into and out of place. The lower threaded end 21 engages in a tapped opening in the lower hanger 17, while the hexagonal head 23 and 110

the upper threaded portion 22 project above the upper surface of the left-hand portion of the bracket 16. The rear portion of the shaft 15 supports an escapement wheel (not shown) which cooperates with the usual escapement dogs to afford letter space feed movements of the carriage and platen under the pull of the motor 8. By lifting or swinging up the feed rack 13 about the pivots 10 it may be disconnected from the pinion 14 and the carriage and platen thereby freed for uninterrupted movements or runs leftward under the impulse of the motor or main spring.

I have shown my invention associated with a tabulating mechanism invented by G. A. Seib and disclosed and claimed in his application Sr. No. 29,874, filed May 13, 1925. Said tabulating mechanism comprises a column-stop bar 24, extending lengthwise of the carriage at its rear and mounted on extensions 25 of the brackets 11 secured to the rear bar 6 of the carriage. Adjustably mounted on the stop bar 24 are one or more column stops 26. Cooperative with the column stops 26 is a notched tabulator stop 27 which is slidably supported on the rearwardly bent ear 28 of a bracket 29, having foot portions 30 which receive screws 31 whereby said bracket is secured to the top plate 3. The tabulator stop or frame stop 27 is connected by rivets 32 with an angular piece 33 at the opposite side of the ear 28, the rivets passing through a slot-way in said ear and the construction being such that the stop member comprising the part 27 and the part 33 is slidably supported on the ear for up and down movement into and out of the path of the downwardly projecting column stops. The laterally extending portion of the part 33 carries a stud or pin 34 which rests on and is supported by the free end of a spring plate 35, said plate having an ear 36 which receives screws 37, whereby the spring plate is secured to the rear face of a lever member 38, pivoted at 39 on the bracket 29. The lever 38 is provided with a nose or extension 40 which overlies the stud 34, said stud being thus confined between the spring 35 and the nose 40. Also the right-hand arm of the lever member is provided with a forward extension 41, terminating in a rounded shoe or lifter 42 which underlies the rack or bar 13. The right-hand end portion of the lever member 38 has adjustably secured to it by screws 43 and 44 an extension 45 to which is pivotally connected at 46 the upper end of an angular link or connector 47, the lower end whereof is pivotally connected at 48 to a tabulator lever 49, fulcrumed at the rear of the machine and terminating at the front in an upwardly extending stem to which is secured a tabulator key 50. When said key 50 is depressed, the lever 49 will swing down

on its fulcrum, thus pulling down the link 47 and the extension 45, thereby rocking the lever member 38 on its fulcrum 39 and causing the inner or right-hand arm thereof to swing upward, carrying with it the spring plate or finger 35 and causing said finger acting against the stud 34 to slide upward the tabulator stop 27 into the path of the column stops. Also the shoe 42 concurrently acting against the under side of the rack 13 will swing the rack upward and release the carriage, which will run or move continuously leftward until arrested by the engagement of the proximate column stop 26 with the projected frame stop 27. On releasing the tabulator key the tabulating mechanism will be restored to normal position by means comprising a spring 51 secured by a screw 52 to the bracket 29, the free end of said spring overlying the extension 41 and constantly tending to swing the stop 27 and the lever 38 downward. It is not deemed necessary more fully to describe the construction and operation of the tabulating mechanism since it is not per se my invention, and is shown herein as an example of mechanisms with which my present invention may be advantageously employed.

In order properly to regulate and control the runs or free movements of the carriage, I have provided a new and improved braking contrivance which is normally inert or inoperative and is rendered automatically effective when the carriage is released for such uninterrupted runs, as by the tabulating mechanism above described.

My improved braking mechanism comprises an angular member or arm shown detached in Fig. 5 and designated as a whole by the numeral 53. Said arm or member comprises a horizontal body portion 54, having at its rear a downward extension 55 terminating in an off-set 56, formed with a slot 57. At the front the body portion 54 has an extension 58 which projects upward at an angle to the body portion and terminates in an inclined end portion 59, to which is detachably secured, as by rivets 60, a contact or plate 61 which overlies the upper end of the rack or bar 13 and is adapted to be engaged thereby. The body portion 54 is formed with a perforation or hole 62 which fits loosely over the rod-like end portion 22 of the stud 19 which projects above the bracket 16. The slot 57 of the braking arm engages with a screw 63 which projects above the bracket 16 and is preferably the stop screw employed with the usual back spacing mechanism of the Remington machine. The check nut 63 which holds the screw 63 in set positions may serve as a stop for the off-set 56, thus limiting movements of the braking member 53 under actuation of the rack 13. The

braking arm 53 rests on and is supported by a yielding or cushion device in the form of a coiled spring 64 which in turn is supported by the head 23 of the member 19.

5 Above the body portion 54 or at its opposite side from the spring 64 is a regulating device in the form of a thumb nut 65 which is threaded on the rod 22 and at its under side is formed with a boss 66 against which

10 the braking device is constantly pressed by the spring 64. The periphery of the nut 65 is preferably knurled or roughened so that it may be turned conveniently. The under face of the boss 66 is preferably

15 scored or formed with radial grooves or depressions indicated at 67, these depressions being adapted to cooperate with a projection 68 on the upper face of the body portion 54 in order to hold the nut 65 in adjusted

20 positions, the devices 67 and 68 providing in effect a detent for the nut 65. The screw 63 serves as a guide to prevent the member 53 from turning about the rod 22 as a pivot. The thumb nut 65 by being threaded downward or upward on the rod 22 not only serves to vary and regulate the tension of the cushion or spring support 64 but also to vary the normal position of the braking arm 53 and the distance of the contact 61

25 from the top of the rack 13. In other words, the nut or abutment 65 provides means for varying and regulating the action or effect of the braking contrivance.

In operation, with the parts related as

30 shown in Figs. 1, 2 and especially Fig. 3, on depression of the tabulator key 50 the frame stop 27 is projected upward and the rack 13 is lifted by the shoe 42, thereby releasing the carriage. As the rack swings upward it contacts with the contact device 61 and acts therethrough on the braking member or arm 53, swinging said member to the position shown in Fig. 4, said member swinging or turning on the thumb nut 65 as a fulcrum. As the braking arm is thus moved by the rack the spring 64

35 will be depressed, reacting on the contact end of the brake 53 and through it on the rack 13 and the carriage on which it is supported, thus braking or retarding the carriage and preventing it from causing a too violent coaction between the tabulator stops. The extent of the braking action may, of course, be conveniently

40 regulated by adjusting the thumb nut 65, the braking effect being increased by screwing down the nut and compressing the spring 64, and correspondingly decreased by unscrewing the nut or turning it to move

45 upward on the threaded rod or screw 22. After the carriage has been arrested by the coacting tabulator stops 27 and 26, the key 50 may be released, permitting the tabulator mechanism and the rack 13 to return to normal position. As the rack or

movable bar 13 swings downward from the Fig. 4 to the Fig. 3 position, the braking member 53 will follow it, said member being restored to normal position by the action of the spring 64. It will be observed 70 that the braking arm is adapted to swing on the cushion device or spring so that the opposite end portions of said arm are alternately raised and lowered.

Various changes may be made without departing from my invention.

What I claim as new and desire to secure by Letters Patent, is:—

1. Braking mechanism for the carriage of a typewriting machine, comprising a braking arm adapted to cooperate with the carriage, and a cushioning device on which said arm is adapted to swing so that its opposite end portions are alternately raised and lowered. 80

2. Braking mechanism for the carriage of a typewriting machine, comprising a braking arm adapted to cooperate with the carriage, and a cushioning device on which said arm is adapted to swing so that its opposite end portions are alternately raised and lowered, said device also restoring said arm to normal position after operation. 90

3. Braking mechanism for the carriage of a typewriting machine, comprising a braking arm effective on the carriage when it is released, and a spring support for said arm mounted on a stationary part of the machine, said braking arm being adapted to swing on said spring support so that the opposite end portions of said arm are adapted to be alternately raised and lowered. 95

4. Braking mechanism for the carriage of a typewriting machine, comprising a braking device effective on the carriage when it is released, a coiled spring on which said device is supported, and means for maintaining said device on its support, said braking device being adapted to swing on said spring so that the opposite end portions of said device are adapted to be alternately raised and lowered. 105

5. Braking mechanism for the carriage of a typewriting machine, comprising a braking arm effective on the carriage when it is released, a spring on which said arm is supported, and means for maintaining said arm seated on its support, said means comprising devices for varying the pressure of said spring against said arm. 115

6. Braking mechanism for the carriage of a typewriting machine, comprising a braking arm that is effective on the carriage when it is released, spring means on which said arm is supported, and a device on which said arm is adapted to pivot when it becomes operative. 125

7. Braking mechanism for the carriage of a typewriting machine, comprising a brake that is effective on the carriage when it is 130

released, spring means on which said brake is supported, and a device on which said brake is adapted to pivot when it becomes operative, said device being adjustable to 5 vary the action of said brake.

8. Braking mechanism for the carriage of a typewriting machine, comprising a device rendered effective as a brake on said carriage when it is released, a coiled spring by 10 which said device is supported and a separate abutment against which said device is maintained by said spring, said abutment serving as a pivot for said device.

9. Braking mechanism for the carriage of 15 a typewriting machine, comprising a braking arm adapted to cooperate with the carriage, a coiled spring by which said arm is supported, and an abutment against which said arm is pressed constantly by said 20 spring, said arm pivoting on said abutment when the carriage is released, said abutment being adjustable to vary the effect of said arm.

10. In a typewriting machine the combination of a traveling carriage, a braking member therefor, a rod on which said member is loosely mounted between its ends, a spring coiled around said rod and serving both as a support and a restoring means for 30 said member, means for preventing displacement of said member from said rod, and a stationary guide for preventing turning movements of said member about said rod as a pivot.

11. In a typewriting machine the combination of a traveling carriage, a braking arm, a rod on which said arm loosely fits, a wire spring coiled around said rod and providing a cushion for said arm, means for 40 compressing said spring and preventing displacement of said arm axially of said rod, and a stationary guide cooperative with one end portion of said arm to prevent it from turning about said rod as a center, the other 45 end portion of said arm acting on the carriage.

12. In a typewriting machine, the combination of a traveling carriage, an arm effective as a brake thereon, an upright rod over 50 which said arm loosely fits, a wire spring coiled around said rod beneath said arm and providing a yielding support therefor, an adjustable thumb nut threaded on said rod above said arm, said nut serving as a pivot for said rod during its braking action, and a stationary guide for preventing said arm from turning about said rod as a center.

13. In a typewriting machine, the combination of a traveling platen carriage, a releasable feed rack thereon, a cooperating feed pinion, a braking arm, a yielding support for said arm, an upright rod on which 60 said arm loosely fits, means for preventing said arm from turning about said rod as a pivot, an abutment with which said arm con-

stantly engages, a tabulator key, and connections controlled by said key effective to release said rack and cause it to coact with said braking arm.

14. In a typewriting machine the combination of a traveling carriage, a braking device therefor, a rod along which said device is slid able, a stationary guide, one portion of said device coacting with the carriage and another portion with said stationary 75 guide, a spring coiled on said rod and supporting said device, and an adjusting nut threaded on said rod at the opposite side of said device from said spring, said nut serving as a pivot for said arm and being 80 operative to vary the location of said arm and the pressure of said spring thereagainst.

15. In a typewriting machine, the combination of a traveling platen carriage, a releasable feed rack on said carriage, a co-operating feed pinion, column stops on said carriage, a cooperating tabulator stop on the frame of the machine, a tabulator key connected to said frame stop, a rack-lifting device operative by said key, an angular braking arm, an upright rod, said braking arm being perforated to fit loosely on said rod, a spring coiled on said rod on which said braking arm rests, a nut on said rod against which said arm is pressed by said spring, a guide for preventing said arm from turning on said rod as an axis, said rack when released by said tabulator key coacting with said arm which is caused thereby to turn on said nut as a pivot and exert a retarding effect on said rack and through it on the carriage.

16. In a typewriting machine, the combination of a traveling carriage, a releasable feed rack thereon, a cooperating feed pinion, 105 a braking arm, a detachable contact on said arm, a guide rod for said arm, a yielding support for said arm, an abutment with which said arm is in constant engagement, a tabulator key, and connections controlled by said key that are effective to release said rack and cause it to operatively engage with said contact, said braking arm pivoted on said abutment during the braking operation.

17. In a typewriting machine, the combination of a traveling carriage, a movable bar thereon, a cooperating feed pinion, a braking arm, a detachable contact on said arm, a yielding support for said arm, a guide rod for said arm, a thumb nut on said rod with which said arm engages, the engaging face of said nut being provided with radial depressions and said arm with a cooperative projection, a key, and connections controlled thereby to move said bar and cause it to coact operatively with said contact during carriage travel.

18. Braking mechanism for the carriage of a typewriting machine, comprising a braking arm that is effective on the carriage 125 130

when released, spring means on which said arm is supported, and a device on which said arm is adapted to pivot during the braking operation, said device being adjustable to vary the normal position of said braking arm.

19. Braking mechanism for the carriage of a typewriting machine, comprising a braking arm that is effective on the carriage when released, spring means on which said arm is supported, and a separate part against which said arm is constantly pressed by said spring, said part being adjustable to vary the normal position of said arm and also to alter the tension of said spring.

20. In a typewriting machine, the combination of a traveling carriage, a key-controlled bar movably mounted on the carriage, a co-acting braking arm overlying said bar but normally separated therefrom, and a

support for said braking arm, said support being adjustable to vary the normal relationship between the coacting arm and bar.

21. The combination with a carriage having a liftable feed rack, of a brake arm overlying said liftable rack, and a spring against which said arm acts when the rack is lifted.

22. The combination with a carriage having a liftable feed rack, of a rocking brake arm, one portion of which overlies said rack, a spring underlying another portion of said brake arm and on which the said arm is directly supported, and a stop limiting the upward movement of said brake arm by the pressure of said spring when the rack is in normal unlifted position.

Signed at Ilion, in the county of Herkimer, and State of New York this 23rd day of December, A. D. 1925.

RICHARD J. LEWIS.
